UNITED STATES PATENT OFFICE.

JOSEPH W. SMITH, OF WESTMINSTER, MARYLAND.

SILO.

SPECIFICATION forming part of Letters Patent No. 691,818, dated January 28, 1902.

Application filed May 25, 1901. Serial No. 61,920. (No model.)

To all whom it may concern:

Be it known that I, JOSEPH W. SMITH, a citizen of the United States, residing at and whose post-office address is No. 79 West Main street, Westminster, in the county of Carroll and State of Maryland, have invented new and useful Improvements in Silos, of which the following is a specification.

This invention relates to new and useful improvements in silos; and the primary object thereof is to construct a device of the character described which is provided with a plurality of normally closed openings whereby easy access may be had thereto.

15 A further object is to provide an improved closure for these openings which may be arranged so as to cause the silo to be air-tight when the closures are in place.

20 A further object is to so arrange the securing-bars that they will form footholds and constitute ladder portions whereby the operator may be provided with convenient means for scaling the silo.

25 A still further object is to arrange the securing-bar for fastening the closure so it may be detached from engagement with the sides of vertical strips of the silo which form the door-frame, thus permitting the door to be forced within the silo, so that access may be 30 easily gained thereinto.

With these objects in view the invention consists in the peculiar construction and novel arrangement, all of which will be specifically described hereinafter and illustrated in the 35 accompanying drawings, in which—

Figure 1 is a fragmentary elevation of a silo, illustrating the manner of attaching the closure. Fig. 2 is a vertical longitudinal section on the line 2 2 of Fig. 1, and Fig. 3 is a 40 transverse section on the line 3 3 of Fig. 1.

Referring now to the drawings by numerals of reference, 1 designates a silo, which may be constructed of usual form, preferably cylindrical, and provided with a plurality of openings 2, arranged in vertical series.

45 3 and 4 designate two vertical strips forming the sides of the door-frame, and the structure is reinforced by hoops 5 and 6.

7 designates a plurality of transverse strips 50 having their ends secured within recesses 7^a, formed in the outer surfaces of the strips 3 and 4.

The openings 2 are closed by doors 9, to the outer side of each of which is pivotally secured a locking-bar 8 by means of a bolt 10, extending centrally through the door and bar and having a nut 11 on its outer threaded end. The side walls of the openings 2 are rabbeted to form shoulders 12 and 13, and the edges of the doors 9 are correspondingly rabbeted to 55 form shoulders 14 and 15. The upper and lower walls of the openings 2 are beveled, as shown at 16 and 17, to fit the correspondingly-beveled edges of the doors 9. The vertical strips 3 and 4 are also recessed, as indicated 60 by dotted lines in Fig. 3, to receive the ends of the pivoted locking-bars 8, so that when the nuts 11 are tightened the bars will be firmly held in horizontal position.

The strips 7 and the bars 8 (when the latter 70 are clamped by the nuts 11) serve as ladder-rounds, by means of which the structure may be easily scaled.

By loosening the nuts 11 the bars 8 may be released from engagement with the recesses 75 in the strips 3 and 4 and turned to the position shown by dotted lines in Fig. 1, after which the doors may be readily forced within the structure to permit access to the contents thereof.

Having thus fully described my invention, what I claim as new, and desire to secure by Letters Patent, is—

1. The combination with a silo provided with a vertically-arranged series of openings, 85 of parallel vertical strips at the sides of said openings, a series of parallel transverse strips having their ends secured in recesses formed in said vertical strips, inwardly-opening doors for closing said openings, and means for locking said doors comprising a bolt extending through the door, a movable bar pivotally secured upon the outer end of said bolt, and fitting the recesses formed in said vertical strips, and a nut for holding the door in close 90 engagement with the walls of said openings, said transverse strips and bars serving as ladder-rounds.

2. The combination with a silo formed with a vertically-arranged series of openings having their side walls rabbeted and their upper and lower walls beveled, of parallel vertical strips secured adjacent to the sides of said openings, a plurality of transverse strips hav-

ing their ends secured within recesses formed in said vertical strips, inwardly-opening doors rabbeted and beveled to fit the walls of the openings, a locking-bar pivotally secured to the outer side of each door, and having their ends fitted in the recesses formed in the vertical strips, and means for clamping said doors in position comprising a bolt extending centrally through said door and locking-bar, 5 and a nut on the outer threaded end of the

bolt, said transverse strips, and said bars when clamped to the vertical strips, serving as ladder-rounds.

In testimony whereof I affix my signature in presence of two witnesses.

JOSEPH W. SMITH.
